(57) **CLAIM**

The ornamental design for “salon shampoo chair”, as shown and described.

DESCRIPTION

FIG. 1 is a perspective view of “salon shampoo chair” showing my new design thereof;

FIG. 2 is a rear side elevational view;

FIG. 3 is a top plan view thereof;

FIG. 4 is a side elevational view; the other side being a mirror image;

FIG. 5 is a bottom plan view thereof; and,

FIG. 6 is a front elevational view.

The criss-cross hatching shading shown on the chair cushion is understood to repeat uniformly throughout the circumscribed area.
